DEVICE FOR EXPELLING THE CONTENTS OF COLLAPSIBLE TUBES

Cornelis Josef Campfens and Hendrik Dalstra,
Middelharnis, Netherlands; vested in the Alien
Property CustodianApplication March 26, 1940, Serial No. 326,088
In the Netherlands April 21, 1939

8 Claims. (Cl. 222—96)

The invention relates to a device for expelling the contents of a tube for liquid, semi-liquid or plastic substances, as generally used. These tubes are made of a metal adapted to be easily deformed. They are mainly of cylindrical shape, tapering towards a flat end where the metal is bent over, and are provided at the other end with a thick and harder metal front plate which cannot be easily distorted and centrally of which nipple is located.

The invention has for its object a device for expelling the contents of tubes of this type which permits of gradually expelling the entire contents as desired.

The expelling device according to the invention consists substantially of a holder mainly having a triangular longitudinal section and a rectangular cross section. The holder has an opening through which the nipple of the tube to be compressed may extend, and a hinged longitudinal wall adapted to be pressed inwardly into the holder. The wall opposite the hinged wall is provided with a depression or recess having such dimensions that during the expelling of the contents of the tube the hard end plate of the tube may be received therein.

In this way the tube may remain within the holder until the last portion of the contents of the tube has been expelled. The depressed portion of the holder, or the recess provided therein, during the gradual expelling of the contents allows the hard end plate of the tube to be left undeformed, while nevertheless the soft tube metal therebelow is entirely compressed. The base of the holder and the hinged longitudinal wall facing it might occupy a symmetrical position with respect to the longitudinal axis of the tube during the whole expelling movement.

According to the invention this effect will still be increased if the depression or recess has such a length that the free front edge of the hinged longitudinal wall when pressed inwardly lies substantially flush with the edge of the depression or recess.

Further, according to the invention, the device may be constructed so that a cover for closing the expelling opening of the tube is swingably mounted so that the hinged longitudinal wall of the holder, while pressing with its edge against a cam or irregular portion of the cover, in its normal position keeps the cover closed, whereas on moving the wall inwardly the cover follows this movement under the influence of a spring and frees the expelling tube.

By a pressure of the thumb on the hinged

wall the cover in front of the expelling opening is lifted and the contents of the tube are expelled. If the pressure is released then the cover is closed again. A closure cap need not be screwed on and off since the tube when out of use is always closed.

According to the invention the device may be constructed so that in a predetermined position of the hinged wall the cover may be turned in such a manner that the cam thereon will become located outside the upwardly directed path of movement of the wall edge. Thus the hinged wall may be turned into an entirely open position and a tube may be inserted into the holder.

Within the spirit of the invention various embodiments and details of the expelling device may be used. Some of these embodiments and details will be described hereinafter with reference to the accompanying drawing, in which

Fig. 1 is a longitudinal section of a tube holder.

Fig. 2 is a front elevational view thereof.

Fig. 3 is a cross section on the line III—III in Fig. 1.

Fig. 4 shows a detail on a larger scale.

Fig. 5 is a partial longitudinal section of a modified embodiment of the tube holder.

Fig. 6 is a partial longitudinal section of a third embodiment.

Fig. 7 is a rear elevational view thereof.

As appears from Figures 1, 2 and 3 the holder 1 has a mainly triangular longitudinal section and a rectangular cross section. From Fig. 2 also the shape is to be seen which in practice has given the best results and which has been chosen so as to afford space for the collapsed material of the tube.

The holder 1 has three stationary side walls and one movable wall 2 which is hinged to the holder at 3. The wall 2 may be pressed inwardly into the holder so that the contents of a tube placed between the wall 4 and the wall 2 will be expelled. The expelling nipple of this tube extends through an oblong hole 5 in the top wall 6 of the holder. The mouth of this nipple is automatically closed by a cover 7 cooperating with the hinged wall 2. This cooperation is obtained in the following manner.

The wall 2 is connected to the holder by a spring 8 in the form of a helical spring around the hinge 3 in such a manner that the wall tends to occupy the position shown in Fig. 1. In this position the edge 9 of the wall 2 presses against an irregular portion 10 of a bearing 11 connected to the cover 7 by a stem 12. The bear-

ing 11 is pivotally and also resiliently (spring 13) connected to the holder.

In the position shown in Fig. 1 the tension of the spring 8 overcomes the tension of the spring 13 so that the cover 7 closes the opening 5. However, if the wall 2 is pressed inwardly then the spring 13 causes the cover 7 to be opened.

In order to permit the wall 2 to be swung entirely outwardly so that a tube may be inserted into the holder the shape of the bearing 11 and the irregular portion 10 thereof are such that in the inwardly pressed position of the wall 2 the cover 7 with its stem 12 and bearing 11 may be turned away entirely, so that the wall 2 may pass (Fig. 4).

The helical spring 8 as shown in Fig. 2 is provided centrally with a portion 14 located within the holder in a substantially flat plane. This portion 14 serves to press the tube in the holder against the base 4 so that the tube, also when its contents have been partially expelled, cannot be shifted.

The top wall 6 of the holder merges into the wall 4 via a depressed portion 15. This depression serves to receive the thicker hard metal front plate of the tube when the material of the tube itself is deformed.

The tube, which initially in entirely filled condition is located on the wall 4, will, at least as regards its axis, be gradually shifted in a direction towards such wall during the expelling operation. For this reason the opening 5 in the top wall 6 has been made oblong. In Fig. 1 a tube in unexpelled condition within the holder is indicated by thin lines.

The edge 9 of the wall 2 in its innermost position substantially is flush with the edge of the depression 15.

In Fig. 5 a device is shown adapted to exert a stronger force on the wall 2, in particular if this wall has approached its extreme innermost position. To this end a lever 16, having a pressure surface 17, is mounted for rotation about the same axis as that about which the cover 7 may be swung, but free therefrom. The lower side of said lever when pressed downwardly moves over the wall 2.

Another device adapted to exert a strong pressure on the wall 2 is shown in Figures 6 and 7. This device comprises a double-armed lever 18 having its fulcrum at 19 on the wall 2. The short front arm 20 of this lever is bifurcated and both ends thereof engage toothed racks 21 fixed to the wall 6. The long rear arm 22 of the lever 18 is urged upwardly by a spring 23. Now, by pressing with the thumb on the arm 22 it is possible to repeatedly depress the wall 2 with increasing force for a short distance.

We claim:

1. A device for expelling the contents of collapsible tubes comprising a holder for the tube having side walls and a top wall, one of said side walls being hinged to said holder at one end thereof, a spring normally urging said hinged wall outwardly, the top wall of said holder having an opening therein through which the nipple of the tube may extend, a cover for closing the opening of the nipple, said cover being swingably mounted at one of the edges of the top wall of said holder on an axis parallel to the axis about which said hinged side wall swings and means for transmitting the movement of said hinged side wall to said cover.

2. A device as set forth in claim 1 in which said transmitting means comprises a stem on

said cover having a bearing pivotally connected to said holder, a spring urging said cover to open position, a cam portion on said bearing adapted to cooperate with the outer edge of said hinged wall in such a way that said wall in its normal position keeps said cover closed while when said wall is moved inwardly said cover under the action of said last mentioned spring will uncover the opening in said nipple.

3. A device as set forth in claim 1 in which said cover is mounted on a stem, a bearing on said stem pivotally mounted on said holder, a cam provided upon said bearing normally cooperating with the free end of said hinged wall and said cam being so formed that when said cover is moved to a certain position, said cam will be located outside the path of movement of the free end of said hinged wall.

4. A device for expelling the contents of collapsible tubes comprising a holder for the tube having side walls and a top wall, one of said side walls being hinged to said holder at one end thereof, a spring normally urging said hinged wall outwardly, the top wall of said holder having an opening therein through which the nipple of the tube may extend, a cover for closing the opening of the nipple, said cover being swingably mounted at one of the edges of the top wall of said holder on an axis parallel to the axis about which said hinged side wall swings and means for transmitting the movement of said hinged side wall to said cover, said spring having a central portion extending inwardly into said holder and being located in a substantially flat plane.

5. A device for expelling the contents of collapsible tubes comprising a holder for the tube having side walls and a top wall, one of said side walls being hinged to said holder at one end thereof, a spring normally urging said hinged wall outwardly, the top wall of said holder having an opening therein through which the nipple of the tube may extend, a cover for closing the opening of the nipple, said cover being swingably mounted at one of the edges of the top wall of said holder on an axis parallel to the axis about which said hinged side wall swings and means for transmitting the movement of said hinged side wall to said cover, a pressure lever pivotally connected to said top wall so that one end of said lever may move over said hinged wall and the length of said lever and the location of its pivot axis being so chosen relatively to the said hinged wall that said lever is approximately perpendicular to said hinged wall when such wall has been moved into its innermost position.

6. A device for expelling the contents of collapsible tubes comprising a holder for the tube having side walls and a top wall, one of said side walls being hinged to said holder at one end thereof, a spring normally urging said hinged wall outwardly, the top wall of said holder having an opening therein through which the nipple of the tube may extend, a cover for closing the opening of the nipple, said cover being swingably mounted at one of the edges of the top wall of said holder on an axis parallel to the axis about which said hinged side wall swings and means for transmitting the movement of said hinged side wall to said cover, a double armed lever pivotally mounted adjacent the free end of said hinged wall, a stationary rack provided upon said holder, a pawl-shaped end provided upon the short arm of said lever cooperating with said rack and a spring cooperating with the long arm of

said lever normally urging said long arm away from said hinged wall so that by pressing on the end of said long lever arm said hinged wall may be depressed by the interaction of said pawl-shaped end with said rack.

7. A device for expelling the contents of collapsible tubes comprising a holder for a tube, one side wall of said holder being hinged at one end of said holder, a spring normally urging said side wall outwardly, the top wall of said holder having an opening therein through which the nipple of the tube extends, a cover for closing the opening in the nipple and means for transmitting the movement of said hinged side wall to said cover.

8. A device as set forth in claim 7 in which said transmitting means comprises a stem upon said cover, a bearing upon said stem pivotally connected to said holder, a spring normally urging said cover to open position, a cam portion upon said bearing for cooperating with the free end of said hinged wall in such a way that when said wall is in normal position said wall maintains said cover in closed position, while when said wall is moved inwardly said cover is permitted to swing open under the action of said last mentioned spring.
